UNITED STATES PATENT OFFICE.

LUDWIG STEFANY, OF PHILADELPHIA, PENNSYLVANIA, ASSIGNOR OF TWO-FIFTHS TO CARL STEFANY, OF PENCOYD, PENNSYLVANIA.

DEVICE FOR EXHIBITING SAMPLES, &c.

SPECIFICATION forming part of Letters Patent No. 623,636, dated April 25, 1899.

Application filed August 23, 1898. Serial No. 689,299. (No model.)

To all whom it may concern:

Be it known that I, LUDWIG STEFANY, a subject of the Emperor of Austria-Hungary, (having resided in the United States one year last past and having declared my intention of becoming a citizen thereof,) residing in the city and county of Philadelphia, State of Pennsylvania, have invented a new and useful Improvement in Devices for Exhibiting Samples, Patterns, Pictures, &c., which improvement is fully set forth in the following specification and accompanying drawings.

My invention consists of a device for exhibiting samples, patterns, pictures, &c., embodying leaves that may be successively opened and means for alternately releasing and holding the leaves, the construction of the parts being hereinafter described and the novel features thereof pointed out in the claims that follow the specification.

Figure 1 represents a top or plan view of an exhibiting device embodying my invention, the same being in open condition and showing part of the lid. Fig. 2 represents a vertical section of the device in open condition, taken on line *x x*, Fig. 1. Fig. 3 represents a view of the inside of one end of the device, taken on line *y y*, Fig. 1. Fig. 4 represents a view of parts shown in Fig. 3 in different position.

Similar letters of reference indicate corresponding parts in the figures.

Referring to the drawings, A designates a casing or a box, from the bottom of which rises the tube B, in which is telescopically fitted the stem C, the top of the latter carrying the follower or rising-and-falling table D, which is pressed upwardly by the spring E.

F designates a series of leaves which are hinged to each other and to one end of the follower D and are adapted to be folded on the follower, as in Fig. 1, or to be opened, as in Fig. 2, after the manner of a sample, display, or exhibition book, a photographic album, or the like, it being noticed that samples, patterns, photographic pictures, cards, &c., may be applied to the leaves and the latter successively presented to view, after which the leaves may be folded one on the other on the follower D and the latter pressed down, after which the cover or lid G of the box is closed

over the leaves, thus preventing rising of the latter. In order to hold the leaves in proper position when open, so as to inspect the objects thereon, the inner face of the lid is provided with the leg H, which in order to be folded is hinged to said lid. When said lid is open, said leg assumes an upright position, owing to the pressure of the spring J, and thus forms a standard on which the open leaves are rested, as shown in Fig. 2. When the lid is closed, the leg is folded against the same and rests flat on the upper leaf.

The follower is provided on its sides with ears K, which are freely fitted on the rods L on the inner sides of the box, so as to guide said follower in its rising and falling motions, and said box has also on said sides the pins M, which are so disposed as to have the follower when at its proper highest point about 70 against said pins as stops, and thus prevent the displacement of the follower from the box.

Connected with the follower at the end opposite to the hinges of the leaves are the springs N, which pass down therefrom and are guided under the pulleys P to a place of connection with the upper leaf, as at Q, said pulleys being mounted on ears R, which depend from the follower below said hinges, by which provision pressure is so exerted on the upper leaf as to open the same, and as the leaves are hinged to each other the pressure is continued to the several leaves, whereby they may be automatically opened or be thrown out of the box and placed in position 85 to successively expose or present the faces of the leaves, as again shown in Fig. 2.

In order to control the leaves so that but one leaf may open or unfold at one time, the ends of the leaves opposite to the hinges thereof are provided with tongues S, which project through a slot in the end of the box into the slot T in the plate U, which is hinged to said end and held against the same by the spring catch or dog V on the box. On the inner face 90 of said plate U is pivoted the dog W, whose nose W' is primarily at the back of the upper end of the slot T and engages with the tongue of the upper leaf, thus controlling the several leaves. The lower limb of said dog W is 100 provided with a thumb-piece or button X, whereby said dog may be operated to remove

its nose from the tongue with which it is engaged.

Mounted on the axis of the dog W is a supplemental dog Y, whose nose Y' in normal position is set back of the nose of the dog W, but below the same, as shown in Fig. 3.

Z designates a link or lever, one limb of which is freely connected with the upper part of the dog W, and the other limb is freely connected with the body of the dog Y, whereby by motion of the dog W is imparted to the dog Y, but in reverse order.

In order to retain the parts in their normal position or to return them to the same, I employ the spring Z', which is connected with the plate U and bears against the dog W. (See Fig. 3.)

It will be seen that when the lid is opened the upper leaf is exposed, and when the other leaves are to be viewed the piece X is pressed down. This operates the dog W and causes it to move in the present case to the right, referring to Fig. 3, its nose then retiring from the tongue of the upper leaf. Simultaneously therewith the dog Y is advanced in the present case to the left, and its nose passes over the tongue of the second leaf and engages with the latter, so as to hold it on the leaves below it. (See Fig. 4.) As the upper leaf is free, the springs N quickly throw it over and upon the lid G, where its inner face is now above, and the second leaf in the box has its upper face exposed. When the thumb-piece is let go, the dogs return to their normal position, the dog Y then retiring from the tongue with which it engages, while the dog W has its nose placed in the path of said tongue, and as the leaves rise the distance of one leaf the second leaf is locked by the dog W. It is evident that by continuing the action of the thumb-piece the other leaves may be released and caused to open, Fig. 2 showing leaves one and two as having been fully open and leaf three as partially open and in the act of reaching its predecessors.

The table D is shorter than the leaves F, and the hinged ends of the latter that rest on said table project beyond the adjacent end of the same, as shown in Fig. 2. The open leaves, or those that rest on the leg H, have no direct support under their hinged ends, but are permitted to bend downwardly under the pressure of the spring N, the hinged ends of the leaves that remain on the table being also permitted to bend downwardly, so that when a leaf is released it is subjected to a downward pull at its hinged end and so is thrown in the present case from left to right or from the table to the leg and then lodged on the latter in the manner above stated.

Secured to the upper end of the box A, around the tongue S, is an open frame A',

which forms a guard for preventing improper contact with said tongues.

When all of the leaves have been opened, 65 the plate U is opened and the leaves returned into the dog, when the plate is closed and the dogs again engage with adjacent tongues, thus controlling the leaves and holding them folded. ^{7c}

Having thus described my invention, what I claim as new, and desire to secure by Letters Patent, is—

1. A follower, means for supporting the same, a series of leaves hinged to each other and to said follower, and means for elevating said follower. ⁷⁵

2. A follower, means for supporting the same, a series of leaves hinged to each other and to said follower, and a spring connected with said follower and leaves for automatically opening the latter. ⁸⁰

3. A follower, a telescopic support therefor, a spring for elevating said support, a series of leaves hinged to each other and said follower, in combination with a spring connected with said follower and leaves for automatically opening the latter and a guide on said follower for said spring. ⁸⁵

4. A series of leaves hinged to each other and a support therefor, and a spring for automatically opening said leaves in combination with means for alternately releasing and engaging said leaves. ⁹⁰

5. In a device of the character stated, a series of hinged leaves, a support on which the same are mounted and tongues on said leaves, in combination with reversely-operating dogs, a support therefor and means for actuating the dogs whereby they may be alternately disengaged from and engaged with the tongues of adjacent leaves. ⁹⁵

6. In a device of the character stated, a series of hinged leaves, a support therefor, and means for successively opening said leaves, ¹⁰⁵ in combination with a primary dog, a supplemental dog, a support therefor and a lever connecting said dogs, whereby the dogs may be operated in reverse direction for alternate engagement with and disengagement from adjacent leaves. ¹¹⁰

7. In a device of the character stated, a series of hinged leaves, a support therefor, a box containing said leaves and support, in combination with a plate movably connected ¹¹⁵ with said box, dogs mounted on said plate and means for operating said dogs in reverse order, whereby said dogs may be alternately engaged with and disengaged from said leaves.

LUDWIG STEFANY.
